K. KNUDSEN

DOLL

Filed May 10, 1927

INVENTOR.
KRESTINE KNUDSEN
BY Harry P. Schmidt
ATTORNEYS.

UNITED STATES PATENT OFFICE.

KRESTINE KNUDSEN, OF OAKLAND, CALIFORNIA.

DESIGN FOR A DOLL.

Application filed May 10, 1927. Serial No. 21,903. Term of patent 14 years.

To all whom it may concern:

Be it known that I, KRESTINE KNUDSEN, a citizen of the United States, residing at Oakland, in the county of Alameda, State of California, have invented a new, original, and ornamental Design for a Doll, of which the following is a specification, reference being had to the accompanying drawing, forming part thereof.

The figure is a perspective view of a doll, showing my new design.

I claim:

The ornamental design for a doll as shown.

KRESTINE KNUDSEN.
